INVENTOR

James H. French,

W. C. Miller

UNITED STATES PATENT OFFICE.

JAMES H. FRENCH, OF WILLIMANTIC, CONNECTICUT.

FIRE-KINDLER.

SPECIFICATION forming part of Letters Patent No. 266,687, dated October 31, 1882.

Application filed May 11, 1882. (No model.)

To all whom it may concern:

Be it known that I, JAMES H. FRENCH, of Willimantic, in the county of Windham and State of Connecticut, have invented certain 5 new and useful Improvements in Fire-Kindlers and Means for Protecting the Same; and I do hereby declare the following to be a full, clear, and exact description of the invention, such as will enable others skilled in the art to which 10 it appertains to make and use the same, reference being had to the accompanying drawing, which forms a part of this specification.

My present invention is in the nature of an improvement upon the package for fire-kindlers made by the process patented to me in Letters 15 Patent of the United States No. 243,240, dated June 21, 1881; and it consists in the omission of all ingredients from the coating that is applied to the box or wrapper, excepting the glue alone.

20 The oil-soaked pieces of wood are wrapped in any suitable wrapper—such as paper or a box—and the package is then varnished with or dipped in ordinary glue, as shown by the shading lines on the outside of the outer wrap- 25 per in the drawing. This coating of ordinary glue is cheaper and more available than any

coating heretofore used, and forms a varnish that is impervious to the volatile gases arising from the oil-soaked wood, thereby preserving the inflammable qualities of the kindlers and 30 decreasing the liability to accident by fire and to discomfort by leakage while the packages are in store.

The mode of application of the coating to the package may of course be varied, as by dipping the wrapper first into the glue and afterward applying the wrapper so coated to the package.

I disclaim what has been secured to me by the Letters Patent aforesaid and what I have 40 described and claimed in two pending applications filed September 7, 1882.

What I claim as new, and desire to secure by Letters Patent, is—

As an article of manufacture, a package of 45 wood or other suitable material saturated with an inflammable oil, and having a wrapper coated with glue, substantially as set forth.

JAMES H. FRENCH.
